By Glenn S. Noble Atty.

UNITED STATES PATENT OFFICE

MICHAEL J. BOYLE, OF CHICAGO, ILLINOIS

METHOD OF APPLYING HEADS TO STEMS

Application filed October 31, 1927. Serial No. 229,984.

This invention relates to the applying of heads or the like to stems or rods and is particularly applicable to the forming of valves, tappets, or other similar articles. It has been proposed to form or secure heads of one kind of metal, such, for instance, as best adapted for forming valves, and the stems of another kind of metal best adapted for this purpose, but such efforts have heretofore proven more or less unsuccessful on account of the difficulty of properly forming the end of the stem and the valve or head and welding them together so that the head will not become loose. In accordance with the present method, I produce valves or tappets with the heads securely welded to the stems so that they are practically inseparable.

In the accompanying drawings:

Figure 1 is a sectional view of the forming device used for forming the heading operation; and

Figure 2 is a similar view showing the position of the parts at the end of the stroke or finishing operation.

In accordance with this invention, I provide a stem 3 which may be either solid, as shown, or of hollow or tubular construction, and a billet 4 from which the head is to be formed. The billet is provided with a hole 5 for receiving the end of the stem, as shown in Figure 1. When the head is to be applied to the stem, they are first heated to a sufficiently high temperature to permit the welding of the head to the stem during the forming process, which will presently be described. In this connection, it will be noted that when the heads and stems are made of the metals now found to be most suitable for these parts for valves, the temperature to which they are heated is greatly in excess of the ordinary temperatures used in connection with forming operations. The stem with the billet applied thereto is inserted in a die 6 mounted in a die fixture body 7 having a central longitudinal opening 8 in which are placed valve stem guides 9, these being changeable for different sized stems. The lower end of the stem also preferably engages with a stem supporting pin 10 which

is also changeable for stems of different sizes or lengths. The lower end of the stem 3 or supporting pin 10, as the case may be, engages with a plunger 11 mounted in the lower end of the body or die support 7. The lower end of the body is threaded, as shown at 12 for receiving a reduced end 15 of the plunger 11, the arrangement being such that the shoulder 16 will engage with the cap to limit the movement of the plunger. A spring 17 is interposed between the cap and an annular shoulder 18 on the plunger and tends to hold the plunger in raised position. The use of such spring pressed plunger forms one of the principal novel features of this invention and springs of the proper size or strength must be carefully selected for use in the manufacture of different sized valves, tappets or the like in order to produce the desired results.

The upper forming die 19, which cooperates with the lower die and with the spring pressed plunger in the forming operation, is secured in the die fixture body or holder 20 in the usual manner, it being understood that these dies are actuated by any ordinary or preferred form of press. When the die 19 moves downwardly or toward the die 6 the billet 4 is pressed or forged to the desired shape in accordance with the form of the dies and the upper end of the stem 3 is mushroomed out or expanded to form a head 21 which consists mainly in a thin annular fin or disk tapering to a sharp edge, this headed portion of the stem fitting within a similarly shaped recess in the head 22 which is formed from the billet 4 and being welded thereto throughout more or less of its area, such welding usually being around the fin-like disk only. During this forming and welding action the stem and billet move downwardly against the pressure of the spring 17 or until the lower end of the plunger 11 strikes the cap 13. The length of this movement may be adjusted by adjusting the cap, and if desired, the tension on the spring may also be adjusted in this manner. I have found that this yielding support for the stem and billet causes a much more uniform forming and welding operation and that the articles com-

pleted in this manner are much more uniform than when the stem and billet are supported rigidly or in the usual manner.

As above suggested, my invention is applicable to forming various articles and may be utilized for various purposes; therefore I do not wish to be limited to the exact method or apparatus herein shown and described, except as specified in the following claims, in which I claim:

10. 1. The method of forming headed articles which consists in applying a billet to one end of the stem heating the same, then subjecting the billet and stem while in heated condition to the action of forming dies to form the desired head, said stem being resiliently supported during a portion of the forming action and rigidly supported during the remainder of the forming action.
15. 2. The herein described method of forming articles which consists in providing a head forming member with a hole therein, then inserting a stem in the hole, then subjecting the head forming member and adjacent portion of the stem while in highly heated condition to the action of forming dies, the stem being resiliently supported during a portion of such forming action to resist the action of one of the dies, and held in fixed position during the remainder of such forming action the operation being such that when the head is formed, the upper end of the stem will simultaneously be spread to form a sharp edged disk-like portion which is welded to the head.
20. 3. A forging and welding method for uniting a head and stem, which consists in inserting the stem in a hole in a billet and heating the billet and adjacent portion of the stem to a high welding temperature, then subjecting the billet and stem while heated to the action of forming dies, during which action, the stem is resiliently supported during a portion of the time, and rigidly supported during the remainder of the time.
